UNITED STATES PATENT OFFICE.

ERNEST R. SEWARD, OF HARTFORD, CONNECTICUT, ASSIGNOR TO THE HARTFORD MACHINE SCREW COMPANY, OF HARTFORD, CONNECTICUT, A CORPORATION OF CONNECTICUT.

METAL-WORKING MACHINE.

1,063,744.

Specification of Letters Patent.

Patented June 3, 1913.

Application filed April 8, 1908. Serial No. 425,961.

To all whom it may concern:

Be it known that I, ERNEST R. SEWARD, a citizen of the United States, and a resident of Hartford, in the county of Hartford and State of Connecticut, have invented a new and Improved Metal-Working Machine, of which the following is a specification.

The invention relates to the class of automatic machines commonly known in the art as screw machines, which machines, however, are not limited to the production of such articles, or, in fact, largely to work upon such devices.

The object of the invention is to provide a machine of this class having numerous and various novel features of advantage and utility.

One form of machine in the use of which the object sought may be attained is illustrated in the accompanying drawings, in which—

Figure 1 is a front view of a machine embodying my invention, on scale reduced from that of the other figures. Fig. 2 is an end view thereof. Fig. 3 is a cross-section on line 3—3 of Fig. 1. Fig. 4 is a longitudinal section of the turret end, as indicated by line 4—4 in Fig. 2. Fig. 5 is a sectional view of the driving mechanism of the machine on plane denoted by line 5—5 of Fig. 4, the driving pulley being shown in full and gear 80 being removed. Fig. 6 represents a development of the multiple cam for actuating the turret. Fig. 7 is a sectional view on line 7—7 of Fig. 4, parts beyond being omitted. Fig. 8 illustrates, in detail, the means for locking the turret against accidental rotation. Fig. 9 is a diagrammatic view showing the cam shaft movement relatively to that of the other operative elements of the machine.

In the drawings 10 denotes the base pan of the machine, supporting at one end the head stock 11, with the work spindle 12 and chuck 13, which may be rotated in any suitable manner as by a pulley 14. The feed mechanism may include the usual slide 15 and its operating cam 16, which latter is mounted on the main cam shaft 17, journaled in suitable bearings in the frame F of the machine, which also carries one or more cross-slides 18, operable by a cam 19 on the shaft 17.

The tool supporting member or turret of the machine includes, in the present in-

stance, a carrier 20 (see Fig. 4) rotatable on a horizontal axis, and having at its ends flanged heads 21, 22 which are journaled in bearings 23, 24, respectively, of the frame F, and in which a series of tool spindles 25 is mounted for reciprocation in such manner that the several spindles (in the present instance four in number) will consecutively be actuated by the reciprocating mechanism as they are, one by one, brought into position for engagement therewith by a step by step rotation of the carrier 20.

The mechanism for moving each tool spindle longitudinally and into engagement with the work is adapted to perform this function at any one of a number of different speeds in order to conform with the mechanical requirements of the tool or cutter carried by the spindle, it being true that in some cases the tool may be fed more rapidly than in others, according to the quality of the metal, nature of cut, or work to be done thereby. Inasmuch as in the present machine each tool spindle is non-rotatable but longitudinally shiftable, I have provided an actuator which is adapted to feed each tool spindle individually at any one of five different speeds, this actuator, as herein shown, consisting of a cam drum 26 secured upon a shaft 27 which is journaled in bearings 28 and is rotated by means to be hereinafter described. The drum 26 carries on its periphery a series of cam strips a, b, c, d, e, (see Fig. 6) the angular pitch of each of which differs from that of another, while the amount of longitudinal movement of the members engaged by said strips and traveling lengthwise of the drum axis f will in all cases be alike, as indicated by the dimension lines α . The cam drum travels in the direction of the arrow g, and while the active portions of the several cam strips vary in length, all of them preferably finish their active movements as well as their full return movements on the same line, respectively, a feature which is desirable in view of the fact that the turret rotating mechanism is timed to commence its action immediately upon the return of each tool spindle to its retracted or normal position.

The manner in which each of the tool spindles is fed toward the work is clearly shown in Fig. 4, and, inasmuch as the construction is similar for all, the following description of one is deemed sufficient to

explain the mode of operation. Each tool spindle 25 is, as above stated, mounted for independent reciprocation in the heads 21, 22 of the turret or carrier 20, which is provided with longitudinal webs 30 (see Fig 3) to engage, in each instance, a collar or similar member 31 adapted to slide on said web and to be firmly secured to the spindle 25 by binding screws 32 which permit said spindle to be variably positioned relatively to the collar 31, so as to vary the movement zone of the tool carried by the spindle, according to the requirements of the work, while the movement zone of the collar 31 remains in all cases constant. In order to permit each collar to be actuated by any one of the cam strips *a*, *b*, *c*, *d*, *e*, the former is provided with a series of apertures or recesses 33, any one of which is adapted to receive a stud 34, clamped in place by a binding screw 35, and projecting beyond the body of the collar, and positioned to be engaged by a particular cam strip on the drum 26, the organization illustrated in Fig. 4 showing that the bottom spindle (which is the active one at present) is operable by the right hand end cam *e*, while the top spindle will, when in the position now occupied by the bottom spindle, be operated by the left hand end cam *a*, each spindle being preferably tubular to receive a spring 36, one end of which is secured to the spindle while its other end is attached to a stationary shell 37 to assist the return portion of the cam strips in retracting the spindle to its normal position, as limited by a buffer or abutment 38 provided on the end of each collar 31.

The adjustment of each tool spindle relatively to its collar may be effected by the operator as follows: By referring to Figs. 4 and 7, it will be seen that each spindle 25 is provided with rack teeth 40 in engagement with a pinion 41 formed on a stud 42 which is journaled in the head 22 of the turret and has a squared projection 43 adapted to be engaged by a socket wrench (not shown) which may be inserted through an aperture 44 in the turret supporting frame, so that each spindle, when in its operative position or in alignment with the work spindle 12, may be shifted relatively to its collar 31, after the binding screws 32 have been loosened, access thereto being afforded by the open front 45 (see Fig. 3) of the turret frame.

The cam drum 26, whereby each tool spindle is fed toward the work, is, as above stated, rotated to operate the tool spindles, this movement being dependent upon that of the cam shaft 17, as follows: The drum shaft 27 carries a pinion 50, rigidly secured to the hub 51 of the drum 26, and in engagement with a gear 52, the hub 53 of which is keyed to the cam shaft 17 and is secured

to a worm gear 54 in mesh with a worm 55 on a transverse shaft 56 (see Figs. 4 and 5). This shaft is journaled in bearings 57, 58 of a bracket 59 attached to the turret frame, and is adapted to be driven at different speeds from a driving shaft 60, either through a slow differential gear mechanism indicated in a general way by 61 and including a pinion 62 and gear 63; or in a direct manner and at high speed through a gear 64 secured to the front end of the worm shaft 56 and engaged by a gear 65 normally loose upon the driving shaft 60 but adapted to be rotatively connected therewith by a clutch collar 66, the position of which is controlled by a lever 67 automatically operated by a cam 68 (see Fig. 4). Rotary movement is imparted to the driving shaft 60 (which is journaled in bearings 69, 70 of a bracket 71) by a bevel gear 72 in engagement with a similar gear 73 secured to one end of the main driving shaft 74, journaled in bearings 75, 76 of an extension 77 of the bracket 71, and carrying a belt pulley 78 which may be driven from any convenient source.

From the above description it will be understood that the present machine includes two independent driving mechanisms, viz.: one for continuously rotating the work spindle, and the other for continuously actuating the cam shaft 17, which latter is, however, rotatable at a high or low speed, and which constitutes the principal member whereby all of the other mechanisms except as stated are directly controlled and driven.

Means are provided for imparting to the turret or tool carrier 20 an intermittent rotation in order to bring its several spindles successively into operative position relative to and in alignment with the work spindle 12, in which position such tool spindle may be reciprocated by the cam drum 26, before the turret is rotated to bring its next succeeding tool spindle into active position, and inasmuch as in the present instance the turret has four tool spindles, its operating mechanism is organized to turn the same rapidly for ninety degrees immediately after the tool carried by each spindle has completed its work effected by that movement of the spindle. This object is accomplished preferably in the manner illustrated in Figs. 2 and 4, in which the main driving shaft 74 is shown carrying a pinion 79 engaging a gear 80, which is loosely mounted upon a crank-shaft 81 journaled in bearings 82, 83. The hub of the gear 80 carries a clutch-sleeve 84 the teeth 85 of which are adapted to be engaged by a clutch collar 86 splined to the shaft 81 and longitudinally shiftable thereon so that in this manner the gear 80 and shaft 81 may be connected for rotation. To the shaft 81 is secured the turret-rotating or actuating member consisting of a

double-crank arm 87 which carries a pair of rollers 88, 89 (see Fig. 2) adapted alternately to engage a disk 90 secured to the outer end of the turret or carrier 20 and having radially disposed slots 91 into which a roller enters during its revolution around the axis of the shaft 81, thus causes said disk and turret to rotate ninety degrees, and then leaves the disk, finally arriving at a normal position of rest shown in Fig. 2, in which the crank arm 87 and turret remain stationary during the longitudinal reciprocation of the active tool spindle 25. The organization of the parts is such that when the disk 90 is at rest the slots 91 therein will lie in a line substantially tangential to the arcuate path of the rollers, and as the rollers enter and leave the slots when in this position, it results that the relative movement of the disk will start slowly, gradually be accelerated, and then come to a slow stop, in which position the turret is locked against accidental displacement by a locking member or bolt 92 (see Figs. 7 and 8). This bolt is mounted for longitudinal movement in the turret frame, or more particularly speaking, in a hardened bushing 93 therein, and has a tapered end 92' to enter a correspondingly shaped aperture in any one of a series of bushings 94 carried by the flange 22' of the turret-head 22 above mentioned, a spring 95 (resting with its outer end against a stationary abutment 96) serving to cause said bolt to engage the flange during the resting period of the turret or carrier.

In order to withdraw the bolt 92 from the turret to permit the latter to be rotated by the crank rollers 88, 89 there is provided a pair of cam-faces 97, 98 (on the back or hub 40 of the crank arm 87) which will engage a pin 99 carried by the bolt 92, and pull the latter outward to release the turret immediately after the active roller 88 or 89 has entered the nearest slot 91 sufficiently to 45 control the turret, and, after the active crank-roller has partially turned the turret, said bolt will again be released from its withdrawal cam, and therefore be moved by the spring 95 into contact with the face of 50 the turret-head 22 ready to snap into the next succeeding bushing 94 whereby the turret will be positioned with its next succeeding tool spindle 25 in exact alinement with the work spindle 12.

55 The clutch collar 86 is shifted to connect the gear 80 with the shaft 81 at the proper time, by means of a bifurcated lever 100, pivoted at 101 and having an arm 102 provided with a roller 103 engaged by either 60 one of a pair of cams 104, 105 carried by the crank-arm 87 to disengage the clutch collar 86 from the teeth 85 and thus arrest the rotative movement of the arm when it has reached its proper position, as shown in 65 the drawings, any accidental further rota-

tion thereof (as from a possible drag of the gear 80 on the shaft 81) being prevented by a spring actuated check-pin 106 against which a pair of stop-pins 107 on the crank-arm 87 may each alternately rest. The 70 spring pressure of the check-pin 106 is, however, such as to be readily overcome when the crank-arm 87 is positively started to rotate, this movement being accomplished by a spring-actuated dog 108 adapted to engage 75 either one of a pair of starting pins 109, indicated in Figs. 4 and 7, and carried by the crank-arm 87. The dog 108 is pivotally held at the end of a lever 110, loosely supported by the pivot pin 101 above-mentioned 80 and having an arm 111 provided with a roller 112 adapted to be engaged by a series of cam plates 113 which are secured to the starting cam disk 114 carried by the cam-shaft 17.

85 From the foregoing it will be understood that the clutch collar 86 is held from engagement with the clutch teeth 85 directly by the cams 104, 105, on the crank-arm 87, so that the collar cannot be moved (as by 90 a spring 115, see Fig. 1) into engagement with said teeth 85 to drive the shaft 81 from the gear 80, during the interval in which the lever 102 is held by a cam 104 or 105, thus maintaining the crank arm 87 95 during this interval in what may be termed its rest position, and it will also be understood that, in order to cause the shaft 81 to be driven by the gear 80, it will be necessary to start the crank-arm 87 in its rotation, 100 which result is accomplished by the starting cam 114 and the several elements operated thereby.

105 The organization of the present machine provides for a turret having four tool carrying spindles, all or a portion of which may be successively brought into engagement with the work (which may then be cut off from the stock-bar, whereupon the latter is fed forward to have its end operated upon, and the tool spindles of the turret are then again successively caused to operate on said bar). In view of this circumstance, the cam drum 26, whereby the reciprocation of the tool-spindles is effected, makes a complete rotation to produce a complete reciprocation of each spindle, making as many rotations as there are spindles operated in a cycle of movement of the turret, and then comes to a rest, during which period chucking, feeding and other operations are performed, whereupon the cam-drum will again become active in reciprocating the turret spindles, which operations are repeated as before. Now, inasmuch as the main cam 115 shaft 17 constitutes the principal member of the machine whereby the successive movements of the several elements are controlled, the movement of the cam drum is properly proportioned to that of the main cam shaft. 120 125 130

in the arrangement herein outlined and in which all four spindles are utilized in a cycle of movement of the turret, the ratio of the gearing between the cam shaft 17 and the cam drum 26 being as five to one; in other words the gear 52 is of such size as to use four-fifths of its circumference for the purpose of causing four complete rotations of the cam drum 26, the remaining fifth of the gear-circumference being idle, as far as any actuation of the cam drum is concerned, during which interval the chucking, feeding, and the other operations by mechanism disposed at the left-hand end of the machine, and also operated directly from the main cam shaft 17 takes place and during said one-fifth rotation thereof.

A cycle of movement of the turret completes the work to be done by the machine upon each article produced thereby, and provision must be made for the lapse of sufficient time between the final and initial operations of the tools in the turret during which chucking, feeding and other operations if necessary may take place. The cam drum makes a complete rotation to produce a complete reciprocation of each spindle in the turret and it will therefore be seen that this pause for chucking and other operations takes place in the interval between the operations of two certain spindles in the turret. In order, however, that this pause shall occur only once in the formation of each piece being made by the machine, and not in the interval between the operations of each of the spindles and consequently a number of times during the making of each piece, the mechanism is constructed in a manner now to be described. In order to interrupt said rotations of the cam drum only at the proper time but furthermore to positively lock the same against accidental movement during its pauses, the gear 52 is mutilated by having a certain number of its peripheral teeth removed, and a locking flange 120 (see Figs 3 and 4) is attached to the side of the gear rim as by screws 121 to coöperate with an arcuate cut 122 in the hub of the pinion 50, so that the cam drum will, during approximately one-fifth of the gear rotation be prevented from movement in either direction, thereby insuring the proper reengagement of the teeth on the gear 52 with those of the pinion 50. By referring to Fig. 3, it will also be noticed that the cam drum 26 is cut away at 26' so that the operator may be enabled to place the operating stud 34 of each tool spindle collar 31 into position to be actuated by that cam strip on the drum 26, which is best adapted for the work to be done by the tool.

Although the pitches of the several cam strips on the drum as illustrated in the drawings are such as to provide a variety of tool-feed speeds which will meet most of

the ordinary requirements it may sometimes, to meet a special requirement, become desirable to substitute one or more other cams for those on the drum, or, perhaps to substitute another drum with a full complement of different pitch cam strips, for the drum in use. In either case the most practicable way of effecting such change will be to remove the drum 26, with its shaft 27 bodily from the machine, and, in order to prevent any mistakes in replacing the drum in proper position relative to its actuating gear, etc., I have provided means which permit the removal of the drum, and its pinion and shaft, only when the pinion 50 occupies a certain predetermined position relative to the gear 52, which position must again be occupied before the parts can be reassembled. The device for assuring this proper reassembling consists preferably of a ring or flange 123 (see Fig. 4) secured to the right-hand side of the pinion 50, so that the latter can not be moved toward the left and out of engagement with the gear 52 except said flange be within that peripheral portion of the gear on which the teeth are absent. The drum shaft must be moved axially toward the left in order to remove it from the frame, inasmuch as the right-hand end of the shaft projects and fits for a short distance into an aperture 124 provided therefor in the frame. Now, inasmuch as the gear 52 carries at its tooth-free or mutilated portion the locking flange 120, it follows that the latter must be removed from said gear in order to allow the pinion 50 and shaft 27 to be moved toward the left for removal.

When it is desired to replace the drum-shaft the conditions above described must necessarily be again met, with the addition that the drum cannot resume any other position, as far as its rotation is concerned, because the periphery of the locking flange 120 necessarily fits into the arcuate cut 122 of the pinion hub, and therefore definitely locates the same before the shaft to be replaced can be removed; the substitute shaft being immediately thereafter placed in position.

The operation of the several machine elements as controlled by, and during each rotation of, the cam shaft 17 has been illustrated by a diagram (see Fig. 9) in which the position of the several elements is indicated by the index-line X, and by swinging this line around in the direction of the arrow X' the successive performance of the several devices and their actuators can be readily followed. From this diagram it appears that the turret cam drum 26 has just completed the last one of its four consecutive rotations (its last tool spindle having, therefore, returned to its normal position in the turret,) and has just been locked by

the locking-flange 120 so as to afford the stock-feeding mechanism time to perform its function during the first one-fifth rotation I of the cam shaft 17. As soon as the stock-feed has been accomplished the cam shaft 17 commences its second one-fifth rotation II, at the beginning of which the crank-arm 87 will be caused to make one-half turn (first by the starting cam 113 and subsequently by the gear 80) for rotating the turret 20 ninety degrees to bring tool-spindle #1 thereof into alignment with the work or stock to be operated upon. At the same time the cam-drum 26 has started on its first rotation, so that, after the turret has been turned as just stated, the particular cam strip for operating the tool-spindle to be now acted upon, will cause one complete reciprocation of the latter. At the completion of this reciprocation the turret will again be indexed or turned, and the other elements will consecutively perform their several functions during the third one-fifth operation of the cam shaft, which action will also be repeated during the fourth and the fifth or last one-fifth rotation IV, V respectively, thereof, so that during one complete rotation of the cam shaft four-fifths thereof will be utilized for imparting four successive rotations to the cam drum 26, such rotations serving to reciprocate the four tool spindles successively relatively to the work or stock-spindle, whereupon the cam shaft 17 commences another rotation and the successive operations are again performed as before.

It will be seen that the cam drum is independently mounted and acts solely to operate the spindles in the turret. In the arrangement of parts in the machine herein illustrated the rate of movement of the cam drum is the same as that of the main cam shaft, although the rate of working speed of the cam drum is constant, and by "working speed" is meant the speed of the drum during the operation of the tools upon a piece of work.

When the cam drum is operating to feed the tools the parts are driven at slow speed, and the drum is driven at the faster speed at all other times during its movement and until the tools are brought up into working position with respect to the blank being operated upon, the drum, however, being disconnected from the main cam shaft when the chucking, feeding and like operations of the machine are taking place.

I do not limit my invention and the scope of the following claims to the foregoing illustration and description of the preferred form in which it has been embodied but contemplate various changes as within the spirit and intent of the invention.

I claim—

65 1. A work spindle with means for oper-

ating it, a turret bearing tools, means for rotating the turret, a cam drum, means for driving the drum at a constant rate of tool working speed, tool operating cams of different pitches separately arranged and spaced apart on the drum, and means whereby, without change of cams, any cam may be made to operate successively on any plural number of tools. 70

2. A work spindle with means for operating it, a turret bearing tools, means for rotating the turret, a cam drum, means for driving the drum at a constant rate of tool working speed, tool operating cams of different pitches separately arranged and spaced apart on the drum, and means whereby, without change of cams, any plural number of cams may be made to operate successively on any tool to produce different feeding speeds of said tools. 75

3. A work spindle with means for operating it, a tool spindle with means for operating it, a cam drum, means for driving the drum at a constant rate of tool working speed, cams spaced apart on the drum each to wholly operate one of said spindles at a different speed from that imparted by another of said cams, connections between said tool and cams separately adjustable and including a member adjustable independently of the cam to adapt all of the cams to the operation of said tool, and connections to impart a complete rotation to the drum at every tool movement. 90 95

4. A work spindle with means for operating it, a turret bearing tools, means for rotating the turret, mechanisms for performing different operations, a cam drum mounted independently of other moving parts, a shaft to drive said drum and directly connected therewith, said connection being interrupted to permit periodical rest of the drum during operation of said mechanisms, and means for operating said shaft. 100 105

5. A work spindle with means for operating it, a turret bearing tools, means for rotating the turret, mechanisms for performing different operations, a cam drum for placing the tools in the turret in operative position, a driving shaft for said drum directly connected therewith, said connection being interrupted to permit periodical rest of said drum during operation of said mechanisms, and means for driving the cam shaft at a different rate of speed during 110 115 120 such disconnection.

6. A work spindle with means for operating it, a turret bearing tools and means for rotating the turret, mechanisms for performing different operations on a piece held by the work spindle, a cam drum for placing the tools in the turret in operative position, a shaft for driving said drum, intermeshing gears in a connection between the cam drum and cam driving shaft, one of 125 130

- 6
12. A work spindle with means for operating it, a turret bearing tools, means for rotating the turret, a cam drum having a series of cams separately arranged thereon side by side extending lengthwise of the 70 drum, connections between the tools and cams arranged to cause operation of any tool by any cam, and means for operating said drum.
13. A feeding mechanism including a turret with means for operating it, spindles mounted in the turret, pins adjustably supported in different predetermined positions on each spindle, and means engaging the pins to reciprocate the spindle each at different rates of speed. 75
14. A feeding mechanism including a spindle mounted for longitudinal reciprocation, a collar secured to the spindle, a contact member, means for removably securing the 80 contact member to the collar at points equally distant each from the other, and means spaced apart the same distance as the points of attachment for said contact member, each of said means being adapted to act upon the contact member to move said spindle. 85
15. A feeding mechanism including a tool spindle with means for supporting it, a contact member arranged for adjustment on the spindle in positions equally distant each 90 from the other, a series of cams arranged to feed a spindle a distance equal to that between the different positions for said contact member, and means for operating and 95 supporting the cams. 100
16. A feeding mechanism including a tool spindle with means for supporting it, openings equally spaced in a part supported by the spindle, a pin removably secured in an 105 opening, a cam drum having cams arranged with the distance between the finishing points thereof the same as the distance between said openings, and means for operating the cam drum. 110
17. A feeding mechanism including a tool spindle, means for supporting it, a member on the spindle having openings equally spaced to receive a pin, a pin adapted to be removably secured in either of said openings, a cam drum having cams arranged to 115 impart movement to the member at different rates of speed and with the distance between the finishing points of the cams the same as the distance between said openings, and means for rotating the cam drum at a 120 constant rate of speed during the operation of a plural number of cams. 120
18. A work spindle with means for operating it, a tool spindle with means for supporting it, said tool spindle bearing a member having openings equally spaced, a pin adapted to be removably secured in either 125 of said openings, a cam drum having a plural number of cams arranged to engage 130
- 5 7. A work spindle with means for operating it, a turret bearing tools and means for rotating the turret, mechanisms for performing different operations on a piece held by the work spindle, a cam drum arranged to place the tools in the turret in operative position, a cam driving shaft, intermeshing gears borne by the drum and the shaft, one of said gears being toothless for a portion 10 of its periphery to permit rest of said drum during the operation of said mechanisms on said piece of work, and means for driving the cam driving shaft.
8. A work spindle with means for operating it, a turret bearing tools and means for 20 rotating the turret, mechanisms for performing different operations on a piece of work held by the work spindle, a cam drum arranged to place the tools of the turret in operative position, a cam driving shaft, geared connections between the drum and cam driving shaft, one of said gears being toothless for a portion of its periphery to permit rest of said drum during the operation of said mechanisms on said piece of work, and means for driving the cam driving shaft at variable rates of speed during the disconnection between the cam drum and main cam shaft. 25
- 30 9. A work spindle with means for operating it, a turret bearing tools, means for rotating the turret, a cam drum, means for driving the drum, cams spaced apart on the drum, and means for transferring the effect of each cam to wholly impart feeding movement to any tool, said drum making a complete rotation for the operation of every tool.
- 35 10. A work spindle, means for rotating it, a tool spindle to coöperate with said work spindle, a cam drum having its axis extending in the same direction as the movement of the tool and with means for operating said drum, cams spaced apart on the drum, and means for selectively transferring the effect of each cam to impart feeding movement to said tool, said drum being adapted to make a complete rotation for every operation of said tool. 40
- 45 11. A work spindle with means for operating it, a tool spindle to coöperate with said work spindle, a cam drum having its axis extending in the same direction as the movement of the tool, a shaft connected with said drum to drive it, cams spaced apart on the drum, and means for selectively transferring the effect of each cam to feed said tool at variable rates of speed, said drum being adapted to make a complete rotation 50 at every operation of said tool. 55

5 said pin to move the same at different rates, the distance between the finishing points of the cams being the same as the distance between said openings, and means for rotating the cam at a constant rate of tool working speed.

10 19. A work spindle with means for operating it, a tool spindle with means for supporting it, said spindle bearing a member having openings equally spaced, a pin arranged to be secured within either of said openings, a cam drum bearing cams each arranged to impart feeding movement to said tool at different rates of speed from that of another cam, the extent of such movement however being the same in each instance, and means for operating the cam drum.

15 20. A tool feed including a spindle bearing a tool, a collar adjustably mounted on the spindle, means for operating the collar and spindle, a rack on the spindle, and a pinion engaging said rack, said pinion having means whereby it may be operated.

20 21. A tool feed including a support for a spindle, a spindle mounted for longitudinal movement in said support, a collar adjustably mounted on said spindle, means for operating the collar, and means for reciprocating the spindle in its support independently of said collar to adjust the relative positions of said collar and spindle.

25 22. A tool feed including a support for a spindle, a spindle mounted in said support, a collar adjustably mounted upon the spindle, means for moving the collar, a pinion borne in a bearing of said support and connected with said spindle and having a part projecting through said support, and means on said part for rotating the pinion.

30 23. A tool feed including a bearing having an opening thereinto, a spindle having teeth and supported for reciprocating movement within said bearing, a collar adjustably mounted on the spindle, and a pinion supported in operative relation to the spindle and having teeth meshing with teeth on the spindle and also having a member projecting opposite said opening and accessible therethrough.

35 24. A feeding device including a bearing having an opening thereinto, a turret supported in the bearing, toothed spindles mounted in the turret, collars adjustably mounted on the spindles, pinions located in the turret head and having a part projecting therethrough, said pinions meshing with teeth on the spindles, and having means whereby they may be operated, means for rotating the turret, and means for bringing it to rest with the projecting part of any pinion accessible through said opening.

40 25. A turret, a number of tools borne by the turret, a tool actuator having a plurality of devices each adapted to feed a plural

45 number of said tools, a member to operate said actuator, said member being arranged to accomplish a complete movement in each complete rotation of the turret, means for disconnecting said actuator and said operating member therefor during a portion of the movement of the latter, and a work spindle supported in operative relation to the turret.

50 26. A turret, a number of tools borne by the turret, a cam drum having cams each adapted to feed a plural number of said tools, a pinion connected with the drum, a gear meshing with the pinion and arranged to have a complete rotation in each complete 55 rotation of the turret, means for disconnecting said gear and pinion during a part rotation of the gear, means for holding the drum against rotation during said disconnection, and a work spindle supported in 60 operative relation to the turret.

65 27. In an automatic machine, a main cam shaft for operating a turret and other parts of the machine, a turret, a number of tools borne by the turret, a tool actuator having 70 a plural number of devices each adapted to feed a plural number of said tools, a member to operate said actuator, said member being arranged to accomplish a complete movement in each complete 75 movement of the turret, means for disconnecting said actuator and said operating member therefor during a portion of the movement of the latter, and means for driving the cam shaft 80 independently of said actuator and said operating member during such disconnection.

85 28. A support, a tool spindle slidably mounted on the support, a spider sustained by the support and arranged to assist the spindle in resisting thrust of its operating 90 part, and means for operating the spindle.

95 29. A turret, a spindle slidably mounted in the turret, a collar adjustably mounted on the spindle, a spider arranged to engage 100 said collar and support the thrust of the part moving the spindle, and means for operating the spindle.

105 30. A turret including a head and spiders extending radially of the turret and arranged to support spindles against the thrust of operating parts, spindles slidably mounted in the turret, and means for operating the spindles.

110 31. A turret rotatably mounted, means including a prime mover and a part disconnected therefrom for rotating the turret, a disengaging member between said parts, and means operated by the movement of said disconnected part for actuating said disengaging member.

115 32. A turret rotatably mounted, means including a prime mover, and a part disconnected therefrom for rotating the turret, a clutch between said parts, and connections between said clutch and said disconnected 120

- part to operate the clutch by movement of said disconnected part.
33. A turret rotatably mounted, means including a prime mover and a part disconnected therefrom for rotating the turret, a disconnecting member between said parts, a lever to operate said disconnecting member, and means operated by the movement of said disconnected part to operate said lever.
34. A turret rotatably mounted, a prime mover and other mechanism for operating the turret, a disconnecting member between the turret and said other mechanism, a lever to operate said disconnecting member, and a cam actuated by the movement of the turret to operate said lever.
35. A turret rotatably mounted, means including a prime mover and a part disconnected therefrom for rotating the turret, a disengaging member between said parts actuated during movement of the turret to intermittently rotate the latter, means operated by a movement of an intermittently rotated part for actuating said disengaging member in one direction, and means for moving it in the opposite direction.
36. A turret rotatably mounted, means including a prime mover and a part disconnected therefrom for rotating the turret, a disengaging member between said parts actuated during movement of the turret to intermittently rotate the latter, means operated by a movement of an intermittently rotated part for actuating said disengaging member in one direction, means for moving it in the opposite direction, and means for moving said actuating member from a position of rest.
- 40 37. A turret, an actuator to rotate the turret, a cam borne by the actuator, means for operating the actuator, connections between said means and the actuator including a disconnecting member, means operated by said actuator for actuating the disconnecting member, and means for moving the actuator from a position of rest.
38. A turret rotatably mounted, an actuator for rotating the turret, said actuator having intermittent movement, means for operating the actuator, a connection between said parts, means for operating said connection in one direction, means connected with a part permanently connected to rotate with the turret for operating the connection in another direction, and means for moving the intermittently operated part from its position of rest.
39. A turret rotatably mounted, means including a prime mover and mechanism disconnected therefrom for rotating the turret, a disconnecting member between said parts, a controller permanently connected with the turret for operating the disconnecting member in one direction, means for operating it in the other direction, and means for imparting initial movement to said actuator.
40. A turret rotatably mounted, means including a prime mover and a part disconnected therefrom for rotating the turret, a disconnecting member between said parts, a lever for operating said disconnecting member, an actuator permanently connected with the turret to operate said lever to disconnect the parts, means for actuating the lever to connect said parts, and means for imparting initial movement to said actuator.
41. A rotating member, an actuator to operate the same, mechanism for operating the actuator, connections including a disconnecting member between parts of said operating mechanism, a lever to operate the disconnecting member, a cam on the actuator to operate said lever in one direction, means for moving it in the opposite direction, and means for moving said actuator from a position of rest.
42. A turret, an actuator arranged to engage the turret, means for operating said actuator, connections between the operating means and actuator including a disconnecting member, a lever for operating the disconnecting member, a cam on the actuator arranged to engage the lever to disconnect and hold it with the actuator at rest, means to initially move the actuator to disengage said cam from the lever, and means for throwing the lever to connect said parts.
43. A turret rotatively mounted, means including a prime mover and a part disconnected therefrom for rotating the turret, a disconnecting member between said parts, means for moving the disconnecting member in opposite directions to engage and disengage parts, and including means controlled by the movement of said disconnected part for operating the disconnecting member in one direction.
44. A turret rotatably mounted, means including a prime mover and a part disconnected therefrom for rotating the turret, a disconnecting member, means for forcing the disconnecting member into position to connect the parts, and means operated by movement of said disconnected part for moving said disconnecting member and holding it to disengage the parts.
45. A turret rotatably mounted, means including a prime mover and a part disconnected therefrom for rotating the turret, a disconnecting member, means actuated by the movement of a disconnected part to operate said disconnecting member to stop rotation of the turret, and means for imparting initial movement to said controlled means to move it from its position of rest and allow actuation of the disconnecting member.
46. A work holder, a carrier, a plural number of tools borne by the carrier, a plu-

5 rality of different speed actuators separately arranged side by side for moving said tools into operative position with respect to the work holder, and a connection with each 10 tool for operation by either of said actuators during a single cycle of operation of the machine.

10 47. A work holder, a carrier, a plural number of tool holders borne by the carrier, a plurality of different speed actuators separately mounted side by side and each arranged to operate a plural number of tools held by the holders, and connections with each tool holder for operation by either of 15 said actuators during a single cycle of operation of the machine.

20 48. A metal working machine including feeding and chucking mechanism, tool holders supported in operative relation to said mechanism, an actuator for said holders, means for moving said actuator, and means for disconnecting it from its moving means during the operation of the feeding and chucking mechanism.

25 49. A work spindle, means for operating it, a turret bearing tools, means for rotating the turret, a cam drum, means for driving the drum at a constant rate of tool working speed, cams spaced apart on the drum each 30 to wholly operate each of said tools, and connections between the tools and cams sepa-

rately adjustable to adapt either tool to either cam.

50 50. A work spindle with means for operating it, a tool spindle, a cam drum, means 35 for driving the drum at a constant rate of tool working speed, cams spaced apart on the drum each to completely feed said tool, each feeding movement taking a complete rotation of the drum, and means for operating the drum.

51. A work spindle with means for operating it, a tool spindle, a cam drum having a series of cams separately arranged thereon side by side and extending lengthwise of 45 the drum, connections between said tool and cams for feeding movement of said tool by each cam separately, and means for operating the drum.

52. A work holder, a tool holder, means 50 for operating a holder including a plural number of actuators spaced apart each to wholly actuate a holder, and connections between the actuators and holder including a projection adapted to be engaged by any 55 one of a plural number of actuators in a single movement of the holder operating means.

ERNEST R. SEWARD.
